UNITED STATES PATENT OFFICE.

JOHN T. KEWISH, OF NEW YORK, N. Y.

AUTOMATIC FIREARM.

Application filed May 31, 1924. Serial No. 717,061.

To all whom it may concern:

Be it known that I, JOHN T. KEWISH, a citizen of the United States, residing in the borough of Manhattan, city, county, and State of New York, have invented certain new and useful Improvements in Automatic Firearms, of which the following is a full, clear, and complete description.

My invention relates to automatic machine rifles. In my United States Patents No. 1,472,126, dated October 30, 1923, and No. 1,502,676, dated July 29, 1924, pending application Serial No. 499,014, filed September 7, 1921, I disclosed automatic machine rifles of this general character and my present invention is in the nature of an improvement upon the same.

An object of the present invention is to simplify construction of rifles of this character, to reduce the weight and decrease the number of parts and to render the operation of the same simpler and more reliable.

Another object of my invention is to provide an arrangement whereby the firing pin and actuator are locked together at the moment of firing, the recoil thrust of the primer acting directly on the firing pin and the resultant action being the same as if the thrust were delivered directly to the actuator.

A further object is to provide a combined safety locking and remounting device which also serves to release the firing pin and actuator at the proper times.

A still further object is to provide a one-piece receiver open at the top provided with recesses for housing the trigger mechanism and magazine.

Another object is to provide a novel removable and slidable casing to inclose the breech mechanism adapted to be fixed thereto when desired, and which carries the sight.

My invention will be better understood from the following description taken in connection with the accompanying drawings and its scope will be pointed out in the appended claims.

In the drawings illustrating my invention:

Figure 1 is an elevational view of a rifle according to my invention, with a part broken away and with the casing also indicated in retracted position in broken lines.

Fig. 2 is a longitudinal view, parts being

in vertical section and parts in elevation of the mechanism of a rifle for both single shot and automatic action, the position of the trigger mechanism for single shot action being shown in dotted lines and for automatic action in full lines, and with the breech mechanism shown in its most forward position.

Fig. 3 is a horizontal section taken substantially on the line 3—3 of Fig. 2.

Fig. 4 is a longitudinal vertical section, with parts in elevation showing the breech mechanism in retracted position, the ejector in operative position and the trigger mechanism in normal position.

Fig. 5 is a view similar to Fig. 4 with the breech mechanism in its forward position and the firing pin cocked and ready for firing.

Fig. 6 is a cross-section taken on the line 6—6 of Fig. 4.

Fig. 7 is a cross-section taken on the line 7—7 of Fig. 1.

Fig. 8 is a cross-section taken on the line 8—8 of Fig. 5.

Fig. 9 is a cross-section taken on the line 9—9 of Fig. 5.

Fig. 10 is a cross-section taken on the line 10—10 of Fig. 3 but with the breech block in position.

Fig. 11 is an enlarged sectional detail taken on the line 11—11 of Fig. 2.

Fig. 12 is a sectional view taken on the line 12—12 of Fig. 3.

Fig. 13 is an elevational view of the bolt.

Fig. 14 is a front end view of the bolt with the extractor shown in place.

Fig. 15 is an enlarged vertical section of the front end of the bolt illustrating the firing pin striking the primer.

Fig. 16 is a perspective view of the spring for locking the firing pin on to the actuator.

Fig. 17 is a top view of the gun shown in Fig. 1 with the cover casing in place.

Fig. 18 is an enlarged sectional detail illustrating a modified form of the rear end of the receiver.

Fig. 19 is a rear end view of the modification shown in Fig. 18.

Fig. 20 is a sectional view taken on the line 20—20 of Fig. 18.

Fig. 21 is a longitudinal vertical section illustrating a modified actuator and firing pin.

Fig. 22 is a side view of the rear portion of a preferable type of cartridge showing the primer sunk below the surface.

Referring to the drawings in which the numeral 1 is a stock, on which is mounted a barrel 2. A receiver or casing 3 is fixed to the barrel 2, and bolted to stock 1 by bolt 1'. As shown in the drawings, particularly Figs. 2, 4 and 5, the receiver is made in one piece, being provided with two compartments 4, 5, in its lower part to receive the magazine and trigger mechanism respectively, and an upper compartment with grooved tracks 6, 6' and 7, 7', indicated in Fig. 7 in which the breech block mechanism and inclosing casing travels as will be more fully described hereinafter. Within the receiver 3, is a reciprocatory weight or actuator 8 in a single piece and receiving power from the primer of the cartridge. Actuator 8 is cut out at its forward end as shown at 9 to receive the bolt 10, the bolt being supported on the firing pin 11, as clearly shown in Figs. 2, 4 and 5. The opposite or rear end of actuator 8 is reduced, as shown at 12, to receive main spring 13, around which the spring 13 is compressed when the actuator is thrust to its rear position by the power of the recoil of the primer at the moment the gun is discharged, and from which rear position the actuator is again sent forward by the recoil of the compressed spring 13, inserting a cartridge in the barrel on its forward stroke and withdrawing and ejecting a shell on its backward stroke, and also to mount a spring member 14, best shown in Figs. 2, 4 and 16, which serves to lock the firing pin 11 and actuator 8 together as well as forming the rear end support for the firing pin spring 15. As shown in Fig. 2, the rear portion of firing pin 11 is hollow to accommodate said spring 15.

The forward end of actuator 8 is provided with a loose pin 16 arranged to engage in a spiral cam groove 17 on bolt 10 to turn the bolt into locking and unlocking position. The bolt 10 has a relative movement to the actuator 8 for the distance of said spiral groove 17, and when the actuator 8 is in its retracted position, shown in Fig. 4, the pin 16 is in the rear end of groove 17 and the bolt itself in its forward position relative to the actuator. In this position a bent right angle flat spring 18 fixed on the forward end of the actuator engages in a recess 19 on said bolt 10 to prevent the turning and retraction of the bolt in that position. As the actuator 8 travels forward through the action of main spring 13, with the bolt 10 in its forward position so held by spring 19, the spring 19 contacts with a lug 20 on the receiver 3, at a point slightly ahead of the final position of the bolt against the cartridge in the barrel and is lifted out of its locking position. The

bolt 10 now being free to turn, the actuator 8 continuing its forward movement, pushes the pin 19 from its rear position in groove 17 to its forward position, thus turning the bolt and locking its lugs 10' and 10'' with lugs 20 and 21 in a manner readily understood, the forward end of actuator 8 and bolt 10 both passing said receiver lugs and abutting the rear end of barrel 2 at this time. 75

The forward end of bolt 10 is countersunk as shown at 22 to receive the head of the cartridge 23. The edge of the central opening 24 of bolt 10 in which firing pin 11 travels is provided with a series of small notches 25, preferably three, as shown in Fig. 14, extending a slight distance below the surface, thus forming a seat to stop the primer from passing beyond that point. In order to enable the firing pin 11 to pass the small projections 25, it is provided with a corresponding series of grooves 26, one of which is shown in Fig. 15, to accommodate said notches. It is of course understood that at this time the bolt 10 has completed its turning movement, and the pin is in the position shown in Fig. 5. 80

The extractor mechanism is best shown in Figs. 6, 9 and 13 and comprises a finger 27 mounted in a dovetail slot flush with the surface of bolt 10 and adapted to engage and withdraw a cartridge from the breech. The finger is maintained in operative position by a spring 28, indicated partly by dotted lines in Fig. 14, which is fulcrumed on the rear end of the bolt as indicated at 29, and forked at its forward end as shown at 30 to clear the lugs on the bolt and engage in cooperating notches 31 on the extractor 27 in a manner readily understood. 95

It will be observed that the lower portion of the bolt is formed with a smaller radius from the center of the bolt than the upper part as shown in Fig. 14, the upper and lower parts being united by flat surfaces, against which said spring 28 is fulcrumed at the rear end of the bolt. As shown in Fig. 16, the spring member 14, is provided with a top flat surface 32, carrying on its under side a stud 33, and at its forward end downwardly projecting prongs 34, the edge of the part 32 between said prongs 34 being preferably curved as shown at 35 to fit a corresponding curvature provided on the larger part of the rear end of the actuator as shown at 36. The object of this arrangement is to permit the prongs 34 to straddle the firing pin 11 at a point ahead of the end of actuator 8 against which the main spring 13 abuts. An opening 37 is provided in the reduced end of actuator 8 to receive the stud 33. The spring member 14 has at its rear end a downwardly extending wall 38 for the purpose of providing a rear abutment for firing pin spring 100

115
120
125
130

15, and is secured in place to the reduced portion of the actuator 8 by means of studs 39 on the actuator engaging in openings 40 provided in suitable wings 40' on wall 38.

6 It will be observed that the spring member 14 is of one piece bent to form the unit described.

As previously indicated, the function of the spring member 14 is to lock the firing pin 11 and actuator together at the moment of firing as well as to form the rear abutment for the firing pin spring. In Fig. 2, the parts are shown in their relative positions at the moment of firing. In this case, 10 the firing pin 11 and actuator 8 are locked together by stud 33 dropping behind the rear end of the firing pin. This locked position is maintained while the breech mechanism is moved to its retracted position 15 shown in Fig. 4, and as it again goes forward to the position shown in Fig. 5. Grooves 41 are provided on the receiver 3 in which the prongs 34 of spring member 14 are free to pass as the mechanism travels 20 as indicated. At an intermediate point, the grooves 41 are provided with ridges 42 adapted to raise the prongs 34 as they pass over the same and thereby lifting the stud 33 out of locking position behind firing pin 25 11, the actuator 8 then being free to move forward to its final position while the firing pin 11 is detained by a lug 43 carried by it 30 engaging with a sear 44 of the trigger mechanism; the detention compressing the firing spring 15, from the recoil of which the firing pin 11 is sent forward to fire the cartridge in the barrel at the moment it is released from sear 44, the lug 43 of the 35 firing pin remaining partly on sear 44 to hold it down while the firing pin 11 is in its forward position. The ridges 42 are positioned to engage the prongs 34 for the purpose of lifting stud 33 out of locked position on the firing pin just before the lug 40 43 engages the sear 44, the prongs 34 being free after passing over the ridges 42, to drop back in grooves 41 and the stud 33 being free to fall back in locking position behind the firing pin 11, when said firing 45 pin is released from engagement with the sear 44 and has moved forward to its firing position. When the pin 11 is in its firing position, a shoulder 45 on the lug 43 is adapted to be engaged by a recocking and locking member 46. The member 46 is in the form of a disc having a threaded stud 47, and is rotatably mounted in the receiver 3 at one side of its longitudinal axis and located at a point at which it may engage 50 the shoulder 45 and prongs 34 at the same time, as shown in Figs. 3 and 10. The member 46 has a cut out section to form a shoulder 48 to engage the shoulder 45 on lug 43 of the firing pin, and an operating handle 49. When the member 46 is rotated anti-

clockwise as shown in Fig. 3, the shoulder 48 engages the shoulder 45 and carries the firing pin 11 to recocking position, the shoulder 48 and handle 49 being then in the positions indicated by broken lines at 48' 70 and 49' respectively. On its upper surface as viewed in Fig. 3, the member 46 is provided with a projection 50, adapted to engage, when said member 46 is rotated, in a groove 51 on the actuator shown in dotted lines in Figs. 2 and 10 when the actuator is in its forward position, at which time the projection 50 is in the position indicated in dotted lines at 50', the purpose being to lock the actuator 8 against the 75 frame of the receiver 3 securely in its forward position. The member 46 is also provided with a tapered cut out surface at 52 in its normal position adapted to receive one of the prongs 34, and lift the same 80 when rotated. On its opposite or lower surface, the member 46 has two cut out sections 53, 54, adapted to receive a spring 55, best shown in Fig. 10, to hold it in either 85 of its positions. The piece 56 is provided 90 in the cut out portion made for member 46 to make its wall uniform.

Sear member 44 is pivoted to the receiver at 58 and has a downwardly extending arm 59, acted upon by a spring 60, and a downwardly extending rear arm 61, adapted to be engaged by a hooked lever 62 pivotally connected with trigger 63 which is pivoted on the receiver at 64. The sear 44 tapers outwardly at 65 to engage with a cooperating tapered projection 66 on the actuator 8. The purpose of this arrangement is to engage the sear 44 with the actuator 8 when the firing pin 11 is cocked, and while the actuator 8 is traveling, to prevent the release of the firing pin 11 by the operator prematurely pulling the trigger before the actuator has reached its final position. 100

The ejector 67, also pivoted on the receiver at 58 is provided with an arm 68, 110 normally urged upwardly by a spring 69. The ejector is depressed by the actuator 8 when the breech mechanism is in its forward position. When the breech mechanism moves to its retracted position, the ejector 115 67 is urged upwardly into a tapered slot 70 in the bolt 10 shown in Figs. 6, 9 and 14, and ejects the cartridge in a well known manner.

The springs 55, 60, and 69 are three fingers of the upper part of a double flat spring, the lower part 71 forming a spring adapted to guide and urge hook lever 62 into engagement with the arm 61 of sear member 44. As shown in the drawings, the trigger 63 extends through a slot 72 in the receiver 3, and since lever 62 is fulcrumed on said trigger at 73 in order to permit the lever 62 to operate when the trigger is pulled, it is provided with a notch 74. Pro- 120 125 130

jecting from the rear of trigger 63 is an arm 75, to which is secured a trigger spring 76, the lower part of said spring 76 being attached to a block 77 slidable in slot 78, shown in Fig. 11, and adapted to assume two positions indicated in full lines at 79 and in dotted lines at 79' in Fig. 2. In position 79, the trigger 63 may be pulled back its full distance so as to release sear 44. In position 79' it may be pulled back but part way until it strikes block 77. In this case, the sear 44 is moved down far enough to release the firing pin 11 while the lever 62 continues to hold the sear 44 down. The former position is provided for automatic action controlled by pulling the trigger while in the latter position, the holding of the trigger permits machine action.

When the breech mechanism is positioned in the receiver 3, it is inclosed by a cover casing 80, having integral therewith upright walls 81, 82, best shown in Fig. 7, for supporting and protecting a suitable rear sight, and a rear wall 83 extending downwards in back of an integral wall 84 of receiver 3 against which the rear end of main spring 13 abuts. The wall 84 may be omitted in which case the main spring 13 may abut directly against the wall 83. The walls 83 and 84 have coinciding openings to receive a locking piece 85, which is rotatably mounted on the wall 83 and fixed in position by a spring 86, the object being to lock the receiver 3 and casing 80 firmly together when the casing is in its forward normal position. At its rear end, receiver 3 is provided with projections 87 extending beyond the wall 84. The projections 87 have a radial groove 88 adapted to receive a cooperating dovetail surface 89 on a portion of the periphery of locking piece 85. In locked position, the dovetail surface 89 on the locking piece is in engagement with the groove 88 of projection 87, and the parts may be unlocked by a partial rotation of the piece 85 to move the dovetail surface 89 out of groove 88. The receiver 3 is also provided with a one piece flat spring catch 90 adapted to lock the casing 80 and receiver 3 together when the casing is in its normal forward position, and also to engage the locking piece 85 and prevent its rotation when in locked position.

On the top of casing 80, the spring 91 usually employed for positioning the rear sight, is extended forwardly beyond its usual fulcrum 92 and is provided at its end with a slot 93, shown in Fig. 17 to receive a locking pin 94, having a pair of oppositely extending studs 95 adapted to fit into an opening 96 in the casing 80. The opening 96 has two slots 97 and 98 cut at right angles in different planes on its edge as shown in Fig. 17, whereby the pin 94 may be seated in the upper of said slots as shown in Fig. 4 to

raise said pin above the inner surface of the casing 80, and in the lower of said slots when rotated 90 degrees so that the end thereof engages in an opening 99 in the actuator 8 thus locking said actuator to said casing, so that the casing and actuator may be firmly secured together for the purpose of moving these parts to the rear to permit reloading and also while so held together to permit hand operation if desired, in which case the parts 81 and 82 may be used as a handle. For normal automatic operation, the pin 94 is out of engagement with actuator 8.

The casing 80 is slidably held in position on the receiver 3 by its dovetailed edges 80', 80" engaging in grooves 7, 7' respectively as indicated in Fig. 7, said grooves being located at a point above the bed of the receiver in which actuator 8 travels and on the inner sides of the receiver walls, the bed being recessed to accommodate spring 13 and slotted in the center to accommodate the trigger mechanism in which the trigger 63, sear 44 and ejector 67 are pivoted. When casing 80 is moved to its retracted position, as indicated in broken lines in Fig. 1, the spring 90 engages the same for the purpose of holding it in this position, said spring 90 being provided with an extended part 90', shown in Figs. 1, 3 and 7, adapted to engage a slot 90" on the casing 80, shown in Fig. 7. When assembling the rifle, the casing 80 is always inserted in grooves 7, 7' on the receiver from the rear, and when the wall 84 is not integral with the receiver, the actuator is similarly inserted in grooves 6, 6'. But when the wall 84 is integral with receiver 3 as previously described, the actuator must be positioned from above, in which case, the edges of grooves 6, 6' are cut vertically as shown in Figs. 7, 8 and 10. The edges of actuator 8 engaging in grooves 6, 6' may be cut away for clearance to reduce friction at all points except at its end, as indicated at 8', 8" in Fig. 4. As shown in Figs. 18, 19 and 20, the wall 84 may be a separate movable piece 84' in a slot 84" on the receiver 3, which acts as the rear abutment for main spring 13, when held in its normal position by spring 90, and which may be pushed down in the slot 84" and folded back to permit the assembly of the breech mechanism from the rear. The wall 84 is held rigidly in position by trunnions 84" which have flattened surfaces, and reinforced in that position by a shoulder 90' on the spring 90 which acts as an abutment.

The magazine 4' is made of a single piece with its walls bent to proper shape so as to provide flexible side walls having a spring action, as shown in Fig. 9, the adjacent walls of the receiver and stock being slightly cut back to permit of this spring action and easy assembling.

In my invention as hereinbefore described 13

it was necessary to withdraw the casing 80 in order to reload the magazine 4. By this arrangement it was possible to make the casing closed at its forward end with the 5 exception of the usual opening 100 through which the shells were ejected and the actuator inclosed without any exterior handle projections for reloading or starting. In Fig. 17, is shown a modified form of casing 10 having an open section 101 at its forward end to permit reloading of gun without the casing being moved from its normal position. In this case it is necessary to have an extension or operating handle 102 on the actuator 15 8.

In Fig. 21 is shown a modification in which the actuator has an extension 103 through the bolt 10, adapted to receive the blow from the recoil of the primer, with 20 the firing pin reduced extending through the same. In this case, the uniting of the firing pin and actuator by means of spring 14 is dispensed with and the firing pin spring abuts against a removable wall 104.

In Fig. 22 is shown a modified type of 25 cartridge in which the primer 105 is positioned in the shell a slight distance below the rear end surface, which arrangement I have found of advantage since after shell 30 is discharged, the primer does not extend out from the shell as is now the case with regulation cartridges. When using this shell, the primer contacting parts of my actuator and firing pin must be slightly extended.

From a consideration of the above description, taken in connection with the drawings, my invention will be apparent without further explanation, and the advantages set forth prior to the detailed description will readily be recognized. I do not wish to be understood as being limited to the details of form or arrangement of parts herein set forth, for various changes 45 may be made by those skilled in the art without departing from the spirit or scope of my invention.

Having thus described my invention, I claim:

50 1. A gun of the class described having a receiver comprising in one piece means for containing the breech mechanism, a cover case, the trigger mechanism, the trigger guard, the magazine; and having parallel 55 tracks to receive the breech mechanism and cover case.

2. A gun of the class described having a receiver comprising upper walls, a slotted bed wall, a lower enclosing outside wall and 60 a vertical central wall, all integral with said receiver, said walls forming an upper breech-block compartment and two lower compartments, said lower compartments housing and supporting respectively the 65 trigger and trigger mechanism and the

magazine, and means on said walls for bolt- 70 ing the receiver to the gun stock.

3. In the class of gun described, a receiver having longitudinal side walls, raised above a bed in said receiver to form an upper compartment, with duplicate parallel tracks in the inner side of said walls to carry breech 75 mechanism and cover case.

4. A gun of the class described having a receiver with an upper and two lower compartments within integral walls of said receiver, said upper compartment having internal longitudinal grooves in its walls, a central slot in bed wall, means for mounting the trigger and trigger mechanism in said 80 slot and means for bringing the mechanism of the upper and lower parts into cooperative relationship.

5. In the class of gun described, a receiver having an upper part adapted to 85 carry the breech mechanism and the cover case, lower parts to carry the magazine and trigger mechanism, and trigger guard on the inside of the lower wall of trigger mechanism compartment.

6. In the class of gun described, a receiver having an upper part adapted to carry the breech mechanism and the cover case, and lower parts to house the magazine and trigger mechanism, respectively, said 90 mechanism including a trigger having a journalized lever thereon, a trigger guard on the inside of the lower wall of said trigger housing part and a slotted bearing guide-way in the upper part of said guard for the 100 lever member on the trigger.

7. In a gun as described, a receiver in one piece having upper longitudinal side walls and tracks therein to receive the breech mechanism, including a main driving spring, and the casing cover, said receiver having separated compartments for the magazine and trigger mechanism, and having an upright rear wall the abutment for the main operating spring, adapted to receive and allow said casing cover to pass over said wall.

105 8. A gun of the class described having a single united receiver and frame, supporting 110 in its upper compartment, in longitudinal 115 grooves inside its walls, the breech mechanism, enclosing the magazine in one lower compartment, and the trigger mechanism in the other, means for cooperating the mechanism of the upper and lower compartments including an internal integral trigger guard 120 on the lower wall of said receiver.

9. A gun of the class described having a 125 united receiver and frame, supporting breech mechanism in longitudinal grooves or tracks in its upper compartment, having means for enclosing magazine, trigger and trigger mechanism in its lower compartments, having an integral lower receiver 130 wall carrying an integral trigger guard, said

- wall forming a solid enclosure and closing all apertures in cooperation with the gun stock, said upper compartment having a rear abuttable main spring wall and means 5 for removal of said wall.
10. A gun of the class described having a receiver carrying breech mechanism in its upper part, and magazine and trigger mechanism in its lower parts, the upper and 10 lower operating parts connected through openings in the bottom of the receiver bed, and having a rear movable wall on said upper part for the abuttal of the main spring, said wall having means necessary to 15 hold it rigid in a slot, and slidable therein to fold out of the way of said main spring.
11. A gun of the class described having breech mechanism including an actuator or traversing weight, carrying a relatively 20 movable bolt and a relatively movable firing pin, and means for locking the actuator and firing pin together and holding them locked at the moment of firing.
12. A gun of the class described having 25 breech mechanism including an actuator, or traversing weight, a bolt and a firing pin, all relatively movable to each other, means for locking the actuator and firing pin together and holding them locked at the moment of discharge of the gun, and means 30 for receiving the recoil thrust of the primer, from said discharge, on the end of the firing pin through which the said thrust is imparted to the actuator.
- 35 13. A gun of the class described having breech mechanism including an actuator, or traversing weight, a bolt rotatably mounted in forward end thereof, and a firing pin slidable longitudinally within said actuator 40 and extending through said bolt, and means for locking the actuator and firing pin together at the moment of discharge of the gun whereby the actuator is impelled by thrust of the primer on the firing pin to 45 carry back the breech mechanism.
14. A gun of the class described having breech mechanism including an actuator, or traversing weight, having a longitudinally 50 slidable firing pin therein, and a relatively movable bolt rotatably mounted within one end thereof journaled directly on said firing pin.
- 55 15. A gun of the class described having breech mechanism including an actuator or traversing weight, a longitudinally sliding firing pin therein, a bolt rotatably mounted in one end thereof journaled directly on said firing pin and means for holding said actuator and firing pin locked together at the moment of firing.
- 60 16. A gun of the class described having breech mechanism including an actuator or traversing weight having a longitudinally slidable firing pin therein, a bolt slidably 65 and rotatably mounted in the forward end thereof journaled directly on said firing pin, and means preventing rotation and retraction of said bolt when it is in its extended forward position relative to said actuator.
17. A gun of the class described having 70 breech mechanism including an actuator or traversing weight carrying a longitudinally slidable firing pin therein, and a bolt slidably and rotatably mounted in one end thereof, journaled directly on said firing pin, said bolt having a countersunk face to receive the head of a cartridge and provided with a plurality of projections, positioned in its central opening at a point slightly below said countersunk surface to 75 arrest the primer and prevent it from passing said point and from coming out of the cartridge.
18. A gun of the class described having 80 breech mechanism including an actuator or traversing weight carrying a bolt movably mounted therein at its forward end, said bolt being formed with a central opening and countersunk face concentric with said opening, and provided with projections extending into said opening slightly below said countersunk face to form a seat for the primer, and a firing pin, slidably movable in said actuator and in said bolt, provided 85 on its forward end with a plurality of grooves to receive said projections in the bolt.
19. In a gun as described breech mechanism including an actuator or traversing weight, a firing pin within the actuator, and a bolt on the firing pin, the bolt, the actuator and the firing pin all having longitudinal movements relative to each other, and means for locking the actuator and firing pin together at their rear ends and holding them locked at the moment of firing.
- 100 20. In a gun as described, a breech mechanism including an actuator or traversing weight, a firing pin within the actuator, and a bolt on the firing pin, the bolt, the actuator and the firing pin all having longitudinal movements relative to each other, and an automatic spring member for locking 105 the actuator and firing pin together at their rear ends at the moment of firing.
- 110 21. A gun of the class described having breech mechanism including an actuator or traversing weight carrying a slidable firing pin within, and a rotatable bolt on the forward end of the firing pin, and automatic means for locking and unlocking the actuator and firing pin in every completed course of the breech mechanism to open and close the breech.
- 115 22. A gun of the class described having breech mechanism including an actuator or traversing weight carrying a slidable firing pin, a bolt journaled on forward end of the firing pin, a main driving spring at the rear 120
- 125 130

- of said actuator, and automatic means for locking and unlocking the actuator and firing pin together with every reciprocal stroke of the breech mechanism, the recoil 5 of the primer sending back the breech mechanism and the recoil of main spring sending it forward.
23. A gun of the class described having breech mechanism including an actuator, a 10 slideable firing pin therein, a spiral slotted bolt movably mounted in forward end thereof and rotatably journaled directly on the forward end of the firing pin locking lugs on said bolt, cooperating lugs in the receiver and a free pin member in the actuator engaging in said spiral slot in the bolt to turn said bolt in and out of locking 15 position by engagement of its lugs with said cooperating lugs in the receiver as the actuator is reciprocated.
24. A gun of the class described having breech mechanism including an actuator, a slideable firing pin therein, a bolt movably and rotatably mounted in forward end 20 thereof, journaled directly on the forward end of the firing pin, a free pin member in the actuator engaging in a spiral slot in the bolt, and means to automatically lock the bolt and actuator together when bolt is in extended forward position on the actuator 25 but releasable therefrom when bolt passes to locking engagement with the lugs of the receiver.
25. A gun of the class described having breech mechanism including an actuator, bolt, firing pin and main driving spring, and having an inclosing casing and means 30 for locking said actuator and casing together, both in movable relationship and in locked relationship on the receiver.
26. A gun of the class described having breech mechanism including an actuator, bolt, firing pin, main driving spring, inclosing casing and means for locking the actuator and casing together, and openings in 35 said casing to permit ejection of shells and to reload the magazine while said casing is in normal inclosing position.
27. A gun of the class described having breech mechanism including an actuator, a bolt, a firing pin, an inclosing casing, a casing and actuator locking member mounted on the surface of said casing and adapted to engage the rear sight at one end 40 and lock said casing and actuator together at the other end.
28. A gun of the class described having breech mechanism including an actuator, a bolt, a firing pin, an inclosing casing, a driving spring and means for locking the actuator and casing together, including a member in the casing rotatable into two 45 positions on said casing to hold said member respectively in and out of locking engagement with said actuator.
29. A gun of the class described having breech mechanism including an actuator, a bolt, a firing pin, a driving spring, an inclosing casing, means for unlocking and locking said actuator and said casing together, the front end of said casing adapted to allow reloading of the magazine and the rear end provided with walls to mount and house the rear sight and with a rear inclosing and driving spring abutment wall carrying a member for locking the said casing to the rear end of the receiver. 50
30. A gun of the class described having breech mechanism including an actuator, a bolt, a firing pin, a driving spring, an inclosing casing and a rotatable grooved locking member attached to the rear wall of said casing adapted to turn in and out of locking engagement on the receiver. 55
31. A gun of the class described having breech mechanism including an actuator, a bolt, a firing pin, a main driving spring, an inclosing casing, a rotatable grooved locking member attached to rear wall of said casing and a spring mounted on the rear end of the receiver to hold said locking member in locked position and adapted to lock and hold the casing in locked position on the receiver independently of said rotatable locking member. 60
32. A gun of the class described having breech mechanism including an actuator, a bolt, a firing pin, a main driving spring, an inclosing casing and a spring mounted on the rear end of the receiver locking the casing and receiver together and having a side extension thereto adapted to engage on the side of said casing to hold the same in retracted position. 65
33. A gun of the class described having breech mechanism including an actuator carrying a slideable firing pin therein formed with a hollow rear section to receive the firing pin and a solid formed section to journal the bolt. 70
34. A gun of the class described having a breech mechanism including an actuator carrying a slideable firing pin therein formed with a hollow rear section and a solid front section, a firing spring in rear section and a bolt journaled directly on front section and supported in said actuator. 75
35. A gun of the class described having breech mechanism including a traversing weight actuator carrying a longitudinally 80 slideable firing pin therein formed with a hollow rear section, a firing spring in said hollow section and means for holding said spring in place forming its rear abutment wall and comprising a part combining the means for locking the actuator and firing pin together at the moment of firing. 85
36. A gun of the class described having breech mechanism including a traversing weight actuator carrying a longitudinally 90

- slidable firing pin therein formed with a hollow rear section, a firing spring in said hollow section, a wall behind said firing spring comprising in part a spring member 5 secured to the reduced rear end of the actuator provided with a stop adapted to engage the rear end of the firing pin and hold the said pin locked on the actuator at the moment of firing.
- 10 37. In a gun of the class described the combination of a receiver having a bed separating the upper from the lower parts and having parallel grooves in said bed on its upper side with raised parts at intermediate 15 points in said grooves, and breech mechanism including an actuator carrying a firing pin formed with a hollow rear section carrying a firing spring therein, and means for locking said actuator and firing pin together 20 at the moment of firing comprising an automatic spring member secured to the rear end of the actuator, and having a rear wall against which said firing spring abuts, prongs on its forward end adapted to ride 25 in said grooves, and a projecting stud or stop adapted to drop behind the firing pin and hold the same at the moment of firing and to be raised when said prongs pass over the raised parts in said grooves thereby 30 locking the firing pin from the actuator to permit locking of the same.
38. A gun of the class described having breech mechanism including an actuator carrying a firing pin therein, a bolt mounted 35 in said actuator rotatably journaled on said firing pin, a detaining sear and a means on said actuator to slidably hold said sear in normal operative position while the firing pin is detained and until the actuator passes 40 to firing position, the sear being then freed from said locking engagement.
39. A gun of the class described having breech mechanism including an actuator carrying a firing pin therein carrying a bolt 45 thereon, a detaining sear to cock said firing pin comprising a member with downward extending arms and a head enlarged to one side and inwardly slanted for engagement with means on said actuator for holding said 50 sear against premature release from said firing pin.
40. A gun of the class described having breech mechanism including an actuator, a firing pin therein carrying a bolt thereon, 55 a detaining sear, a spring under said sear, and a trigger carrying a lever journaled thereto, said lever operating to disable the sear through contact with one of the arms of said sear, and said spring by contact with 60 the other arm of said sear operating to return the sear to normal position.
41. A gun of the class described having breech mechanism including an actuator, a firing pin therein carrying a bolt thereon, 65 a sear member and a lever hooked at one end

for engagement with said sear and journaled on the trigger at the other end in a manner permitting a limited rotatable movement while being withdrawn by action of said trigger. 70

42. A gun of the class described having breech mechanism including an actuator having a slidable firing pin carrying a bolt thereon, a sear, a journaled trigger lever and a trigger adapted to fulcrum against 75 said lever near its journaled bearing to depress said lever from contact with said sear when withdrawn by said trigger.

43. A gun of the class described having breech mechanism including a receiver, a 80 traversing weight actuator, a firing pin carried within the actuator, a bolt thereon, a sear member and an ejector pivoted alongside said sear member in the receiver and on the same pin, said ejector being depressed by 85 the actuator and elevated to ejecting position by a spring under its forward arm.

44. A gun of the class described having breech mechanism including a receiver, a 90 traversing weight actuator, a firing pin carried with the actuator, a bolt thereon, a sear member, a spring means holding the actuator and firing pin locked together at the moment of firing and a recocking and locking member adapted to release the firing pin 95 from its locked engagement with the actuator and to retract and recock it at the same time.

45. A gun of the class described having breech mechanism including a receiver, a 100 traversing weight actuator, a firing pin carried within the actuator, a bolt thereon, a sear member, a spring means holding the actuator and firing pin locked together at the moment of firing, and a recocking and locking member to unlock the firing pin 105 from the actuator and to recock it on the sear, and to lock the actuator and receiver together, all at the same time.

46. A gun of the class described having 110 breech mechanism including a receiver, a reciprocating actuator, a firing pin therein and a bolt thereon, a sear member and ejector pivoted to the receiver, a spring firing pin-actuator locking member mounted on 115 the actuator, and a rotatable releasing, recocking and locking firing pin-actuator member mounted in the receiver.

47. A gun of the class described having 120 breech mechanism including a reciprocating actuator, a firing pin therein and a bolt thereon, a sear and an ejector, a spring firing pin-actuator locking member, and a firing pin-actuator recocking and locking member. 125

48. A gun of the class described having breech mechanism including a reciprocating actuator, a firing pin therein and a bolt thereon, a sear and an ejector, a spring firing pin-actuator locking member, and a 130

firing pin-actuator recocking and locking member, comprising a groove and cam surface to lift said spring firing pin-actuator locking member, a dog to lock on the actuator, and a cut-out shoulder to engage the sear lug of the firing pin, all cooperating to their functions at the same time by a partial rotation of said recocking-locking member, the said member being adapted 10 on its under side to receive a spring to hold it in locked and unlocked positions.

49. A gun of the class described having breech mechanism including a receiver, a reciprocating actuator, a firing pin therein 15 and a bolt thereon, a sear, an ejector, a spring firing pin-actuator locking member, a firing pin-actuator recocking and locking member, a trigger and trigger-journalized lever, and a spring mounted in the receiver 20 comprising a lower part, and an upper part divided into three fingers, the lower part to support and guide the trigger-journalized lever in engagement with the sear, the upper fingers to engage one with the ejector, one 25 with the sear, and one with the recocking-locking member.

50. A gun of the class described having breech mechanism including a receiver, a reciprocating actuator having a firing pin 30 therein and a bolt thereon, a sear member, a trigger and a journalized lever, and a dog mounted in lower wall of the receiver longitudinally slidable to disable the trigger and turn the mechanism of the gun into 35 machine action.

51. A gun of the class described having a receiver carrying breech mechanism in the walls of its upper part including an actuator centrally hollowed to receive a firing pin having a cut-out section in front to receive a bolt and to pass over the locking lugs in the receiver, slanted edges at the 40 bottom of its sides to form tracks, a re-

duced rear end to house the firing spring and receive the main driving spring, and 45 having means for operation by hand.

52. A gun of the class described having a receiver carrying breech mechanism in the walls of its upper part including a centrally hollowed actuator having a firing 50 pin therein, and a bolt with a reduced radial lower half, a countersunk face, projections in its center opening slightly below its countersunk face, a dovetail groove on 55 forward face to carry an extractor flush with forward end of bolt, a spiral slot for turning the bolt and a forked spring, grooved into said extractor at its sides, and fulcrumed at the rear of said bolt.

53. A gun of the class described having 60 a receiver carrying breech mechanism in the walls of its upper part, trigger mechanism in one compartment of its lower part, and a flexible magazine in the other part, having spring action and removable, but 65 integral with the receiver when in operation.

54. A gun of the class described having a receiver and breech mechanism including 70 a reciprocating actuator a bolt and firing pin within said actuator, a main driving spring behind the same and a slideable covered casing combining a means adapted for hand operation when the actuator and said casing are locked together. 75

55. A gun of the class described having breech mechanism including an actuator, a firing pin supported within said actuator, a bolt supported thereon, and a main driving 80 spring, said actuator propelled forward by said spring, inserting a cartridge in the barrel, locking said mechanism and closing the breech, and thrust rearwardly by recoil from the primer of said cartridge through the intermediacy of said firing pin.

JOHN T. KEWISH.
